UNITED STATES PATENT OFFICE.

CHARLES E. SCHWAB, OF LYONS, NEW YORK.

COMBINED CHUTE AND BAG HOLDER.

Application filed February 24, 1922. Serial No. 538,885.

To all whom it may concern:

Be it known that I, CHARLES E. SCHWAB, of Lyons, in the county of Wayne, in the State of New York, have invented new and useful Improvements in Combined Chutes and Bag Holders, of which the following, taken in connection with the accompanying drawings, is a full, clear, and exact description.

10 This invention relates to a combined chute and bag holder adapted to be used more particularly in the transfer of coal from a relatively large receptacle or reservoir to a smaller receptacle, such as a bag or equivalent carrier, the main object being to provide the delivery end of the chute with a movable closure and relatively movable bag holding elements capable of being released from their holding positions simultaneously with the operation of the closure from its open to its closed position and also of restoring said elements to their holding positions when the closure is opened.

25 Other objects and uses relating to specific parts of the device will be brought out in the following description.

In the drawings:

Figure 1 is a face view of the discharge end of a chute and its supporting means in which the closure is open and the bag holder in its holding position.

30 Figure 2 is a side elevation of the same device showing by dotted lines the bag-holder in its released position and the gate as closed.

35 Figure 3 is a longitudinal sectional view taken on line 3—3, Figure 1.

Figure 4 is an enlarged detail sectional view taken on line 4—4, Figure 3 showing one of the pivotal bolts for the gate-supporting frame.

40 The chute forming the subject matter of this invention is adapted to be secured to an inclined portion —A— of the main receptacle having an opening —a— in its lower end through which the coal or other material is adapted to discharge and comprises a pair of metal plates —1— secured to the outer faces of opposite sides of the receptacle —A— for receiving and supporting a pair of extension plates —2—, which are hinged at —3— to the plates —1— for lateral swinging movement when desired to remove or replace the parts carried by the extensions, said plates constituting the main 45 body of the chute and are disposed in a forwardly and downwardly inclined plane di-

rectly over the inclined bottom as —a'— of the receptacle —1—.

The plates —2— extend downwardly and forwardly some distance beyond the lower or front end of the bottom —a'— for receiving and supporting an extension metal plate bottom —4—, which is secured to the side plates or extensions —2— by bolts —5— with its upper rear end overlapping slightly upon the adjacent front end of the bottom —a'— as shown in Figure 3, thereby holding the extensions —2— in fixed spaced relation.

50 A U-shaped sheet metal frame —6— has its opposite arms —7— pivotally connected by bolts —8— to the side plates —2— to swing about a horizontal axis to and from a substantially horizontal position as shown in Figure 2 and is provided with a gate or closure —9— concentric with the axis of the pivots —8— and movable across the lower front edge of the bottom plate —4— in close proximity thereto to and from a position across the open lower front end of the chute and also to and from a position beneath the plate —4— to regulate the flow of coal or other material through the discharge end of said chute, the side plates —7— of the frame —6— being in close proximity to the outer faces of the plates —2—.

55 A catch plate or detent —10— is pivoted at —11— to and between suitable spaced lugs —12— on the cross-plate as —13— of the frame —6— to swing toward and from said cross-plate and into and out of engagement with the inner ends of the bag-supporting levers as —16— and against a limiting stop —14— and is provided with a handle —15— by which it may be operated and which also serves as a means for rocking the frame —6— about the axis of its pivot —8—, the stop —14— being normally spaced apart from the catch plate to allow a limited movement of the free end thereof for a purpose presently described.

60 A pair of bag-supporting levers —16— are pivoted at —17— to the front face of the cross-plate —13— near the opposite sides and lower edge of the frame —6— to swing in a plane parallel with said cross-plate —13— into and out of engagement with suitable stop rests —17—, which latter are secured to the plate —13— to limit the downward swinging movement of the levers —16— to a substantially horizontal position. These levers extend toward each other from

their pivots below the opposite ends of the lower edge of the catch plate —10—, which serves to normally hold the members —16— against their respective seats —17— but 5 may be withdrawn from its holding position to release said members, the inner ends of the members —16— being somewhat longer than their outer ends to permit them to return by their own weight to their respective 10 seats —17'—.

The outer ends of the levers —16— extend some distance beyond the opposite sides of the frame —6— and are slightly curved upwardly to form hooks —18— for receiving 15 and supporting the front side of a bag —B— or equivalent receptacle.

A pair of levers —20— are pivoted to the opposite side plates —2— at the outer sides thereof to swing vertically for receiving and 20 supporting a pair of bag-holding members —22—, which are pivoted thereto at —23— to extend in opposite directions therefrom, said members —22— having their upper front ends pivoted at —24— to the side 25 plates —7— of the frame —6— some distance in front of the pivots —8—, the lower rear ends of the members —22— being provided with hook-shaped extremities —25— for receiving and supporting the rear side 30 of the bag —B—, Figure 2.

In other words, the levers —20— are pivoted to the side plates —2— some distance to the rear of the side plates —7— of the frame —6— and extend downwardly and 35 forwardly from their respective pivots beyond the pivots —8—, while the members —22— extend crosswise of the levers —20— on the free ends thereof with the hook-shaped extremities —25— normally extending rearwardly beyond the pivots —8— when the gate —9— is opened.

The forward end of the frame —6— is normally held against downward movement 40 beyond the horizontal plane by the engagement of the rear edge of the gate —9— with the underside of the plate —4—, which as previously stated is fixed to the side plates —2— of the chute.

The weight of the handle —15— projecting forwardly from the catch plate —10— normally holds said catch plate against the front face of the cross-plate —13— where it engages the upper edges of the adjacent ends of the levers —16— to hold the latter against upward displacement while the outer extremities —18— are supporting the front portion of the bag —B—.

When the frame —6— is in its normal horizontal position with the gate —9— open, the bag-supporting members —22— will extend downwardly and rearwardly from their pivots —24— to support the rear side of the bag and allow the coal or other material to flow from the chute into said bag.

When the bag is filled, the operator raises

the handle —15— to the position shown by dotted lines Figure —2— thereby withdrawing the catch plate —10— from holding engagement with the levers —16— to release said levers and to allow their hook-shaped extremities —18— to rock downwardly and inwardly for releasing the front portion of the bag.

A continued upward movement of the handle —15— will rock the frame —6— upwardly by reason of the engagement of the catch plate —10— with the stop pin —14— and this latter operation will carry the bag-supporting members —22— upwardly and rearwardly to withdraw the hook-shaped extremities —25— forwardly and downwardly for releasing the rear portion of the bag so that the latter with the load therein may be removed, it being understood that during this lifting movement of the frame —6—, the gate —9— will thereby be moved across the lower end of the chute to cut off further flow of the material into the bag.

In other words, the upward rocking movement of the frame —6— not only closes the open end of the chute but also releases the filled bag or other receptacle. While the frame —6— is still held in its extreme upward position to close the gate —9—, the filled bag may be removed and replaced by an empty bag, the open end of which may be held by hand in position and engaged by the hook-shaped extremities —18— and —25— of the bag-supporting levers —16— and —22—, respectively, whereupon the frame —6— is returned to its normal position by means of the hand levers —25— to cause the members —16— and —22— to support said bag, it being understood that the catch lever —10— has been previously operated to allow the member —16— to assume their normal positions against the seats —17— where they are temporarily held by the return of the catch plate —10— to its normal position.

What I claim is:

1. In combination with a chute, a frame pivoted to the chute for swinging movement in either of two opposite directions and provided with a gate movable to and from a position across the discharge opening in the chute as the frame is rocked in opposite directions, movable bag-supporting members on the frame, a catch plate for holding said members in operative position for holding the bag, a stop for limiting the movement of said catch plate and a handle on the catch plate for tripping the same against the stop and thereby releasing the bag-holding members from their holding positions.

2. In combination with a chute, a frame pivoted to the chute and provided with a gate movable to and from a position across the discharge opening of the chute as the frame is rocked in opposite directions, and

bag-holding members pivoted to the frame and movable therewith out of holding engagement with the bag when the frame is rocked to close the gate.

5. 3. In combination with a chute, a frame pivoted to the chute and provided with a gate movable to and from a position across the discharge opening in the chute when rocked in opposite directions, a pair of bag-holding levers pivoted to the frame, a catch plate movable into and out of engagement with said levers for holding them in operative engagement with the bag, said catch plate being provided with a handle for tripping the same to release the bag-holding members, and means for limiting the movement of the catch plate, whereby a continued movement of the handle in the same direction for tripping the plate will rock the frame upon its pivot to close the gate.

4. In combination with a chute, a frame pivoted to the chute and provided with a gate movable to and from a position across the open end of the chute as the frame is rocked in opposite directions, bag-holding

members movably mounted on the frame and normally in position to hold a bag when the gate is closed, said bag-holding members being moved from their holding positions when the frame is operated to close the gate. 30

5. In combination with a chute, a frame pivoted to the chute and provided with a gate movable to and from a position across the open end of the chute as the frame is rocked in opposite directions, bag-holding members movably mounted on the frame and normally in a position to hold the bag when the gate is open, a catch for holding said members in operative position when the gate is open, means for releasing the 35 catch, and additional means actuated by said catch when released for rocking the frame to close the gate.

In witness whereof I have hereunto set my hand this 14th day of February, 1922. 40 45

CHARLES E. SCHWAB.
